UNITED STATES PATENT OFFICE.

CHARLES SCHLOSSOW, OF DETROIT, MICHIGAN, ASSIGNOR TO STANDARD SANITARY MANUFACTURING COMPANY, OF PITTSBURG, PENNSYLVANIA, A CORPORATION OF NEW JERSEY.

DESIGN FOR A FLUSHING-TANK.

SPECIFICATION forming part of Design No. 35,897, dated May 6, 1902.

Application filed April 14, 1902. Serial No. 102,936. Term of patent 7 years.

To all whom it may concern:

Be it known that I, CHARLES SCHLOSSOW, a citizen of the United States, residing at Detroit, in the county of Wayne and State of Michigan, have invented and produced a certain new and original Design for a Flushing-Tank, of which the following is a specification, reference being had therein to the accompanying drawing, in which the flushing-tank is shown in perspective.

A is a body of general rectangular form. The front of this body comprises a plain panel B, bounded at the sides by the vertical columns C, which form rounded corners between the front and ends.

D is the top, and E is the bottom, both of which project slightly beyond the face of the panel and have correspondingly-shaped edges.

F and G are moldings of waving contour 20 adjacent to said top and bottom and forming a border for the panel.

The leading feature of the design is the body of general rectangular form, having a plain front panel bounded at its sides by vertical columns and at top and bottom by a molding of waving contour.

What I claim as my invention is—

The design for a flushing-tank, substantially as herein shown and described. 30

In testimony whereof I affix my signature in presence of two witnesses.

CHARLES SCHLOSSOW.
